UNITED STATES PATENT OFFICE.

JOSEPH E. MYERS, OF THE UNITED STATES ARMY.

INSERTION-PAD HOLDER.

Application filed May 19, 1921. Serial No. 470,773.

To all whom it may concern:

Be it known that I, JOSEPH E. MYERS, of the United States Army, a citizen of the United States of America, have invented 5 certain new and useful Improvements in Insertion-Pad Holders, of which the following is a specification.

My invention relates to devices for holding insertable pads, check books, and the 10 like.

An object of my invention is to produce a holder for such pads wherein the pads may be inserted with accuracy and with 15 little effort, and from which they may not be easily or accidentally removed.

Another object is to produce a pad holder of simple design, which may be made easily and cheaply.

A further object is to provide, in such 20 holders, saw-tooth means for engaging and positively holding the side edges of the pad, whereby the individual leaves are but slightly disturbed and not damaged.

My invention comprises those novel parts 25 and combinations thereof which are shown in the accompanying drawings, described in the specification, and particularly defined by the claims terminating the same.

In the accompanying drawings I have 30 shown my invention in forms which are now preferred by me.

Figure 1 is a perspective view of a preferred form of my device in use to hold a check book stub, parts of the check book 35 and cover being broken away.

Figure 2 is a section through one side of the pad, showing the manner in which it is secured in the holder.

Figure 3 is a view similar to Figure 1, of 40 a modified form.

Figure 4 is a view thereof similar to Figure 2.

Figure 5 is a perspective view of a further modification.

A flange 3, upturned from an end of a base 1, serves as a stop against which the end of a pad or check book stub 2 abuts. The flange 3 may be made separate from the base 1, and be secured thereto, or formed from 45 the same piece of metal, as is shown herein. In the preferred form shown in Figures 1 and 2, the ends 4 of the flange 3 are bent inwardly so that they are parallel to the side edges of the stub or pad 2, and are again bent at right angles, as shown at 5, inwardly towards the pad edges. This forms 50

inwardly facing holding jaws, and when these are provided with serrated vertical edges the pad is securely held thereby.

The metal of which this holder is constructed should be somewhat resilient. As the arms 4, carrying the pad-engaging teeth, are supported only from one edge, there is a certain flexibility in the jaws thus formed.

The shape of the teeth is relatively unimportant, although I have shown the preferred form of these, in Figures 1 and 2. The uppermost tooth, 6, has its upper edge decidedly inclined downwardly. The upper and lower edges of the lower teeth 7 are nearly straight and parallel, and terminate in a downwardly inclined point. The teeth are all spaced, and the edge of the metal extending between them is vertical.

The pad is inserted by pressing it downward between the jaws 4. The resilience of these jaws, and the action of the stiff pad upon the inclined upper surfaces of the teeth 6 permits spreading of the jaws sufficiently to receive the pad. Once in place, the teeth 7 fit between individual leaves, the edges of which abut against the vertical edges of the metal joining the teeth, as shown in Figure 2, and the pad can only be removed with difficulty. The engagement of the holder is only with the side edges of the pad or stub book, near one end, leaving the entire surface thereof free for writing. It is easy to remove a single leaf at a time, as the leaf itself is flexible, but a pad is sufficiently stiff to resist attempts to remove it.

Figure 3 illustrates a modified form, wherein slots 31 are provided in the ends of the flange 3, near its ends. Through 95 these slots are passed the ends of the resilient strip 41, which carry the arms 4 and teeth 6 and 71. These teeth 71 differ from the teeth 7 only in that they are broader and are not spaced at their bases. They 100 are substantially duplicates of the tooth 6. It is apparent that other types of teeth, or the type shown in Figures 1 and 2, might be employed here, if desired.

The pad is inserted as described above, 105 but it may be withdrawn by pressing the strip 41 towards the flange 3. This spreads the arms 4, and disengages the teeth from the pad.

In the construction shown in Figure 5 110 the arms 42 are pivoted at 43 upon the ends of the flange 3. A spring 44 at each pivot

tends to close the jaws inward. Small release arms 8 are bent outwardly from the arms 42, by means of which the jaws may be opened to release the pad.

5 In all forms it is desirable to permanently secure the base to a support, and any suitable securing means may be employed. I have shown, in Figures 1, 2, and 3, triangular lugs 11 cut partly from the metal of 10 the base, and bent downward therefrom to pass through the check book cover 9, and then laterally, to hold the device in place.

What I claim as my invention is:

1. An insertion pad holder comprising 15 a base, an end flange upturned therefrom,

holding jaws resiliently supported from said flange, and downwardly-inclined teeth inturned from said jaws to engage only the side edges of a pad.

2. Pad-holding means for insertion pad 20 holders comprising two sets of opposed, vertically-spaced, resiliently connected, and downwardly inclined teeth adapted to engage only the side edges of a pad and to be inserted between leaves thereof, the edge 25 of the material between teeth being vertical.

Signed at Seattle, King County, Washington this 18th day of March 1921.

JOSEPH E. MYERS.
